UNITED STATES PATENT OFFICE.

FRANK J. KIMBALL, OF LOS ANGELES, CALIFORNIA, ASSIGNOR TO FRANK J. KIMBALL COMPANY, OF LOS ANGELES, CALIFORNIA, A CORPORATION OF CALIFORNIA.

ROTARY WELL-PUMP.

1,245,466.

Specification of Letters Patent.

Patented Nov. 6, 1917.

Application filed February 3, 1916. Serial No. 75,916.

To all whom it may concern:

Be it known that I, FRANK J. KIMBALL, a citizen of the United States, residing at Los Angeles, in the county of Los Angeles and State of California, have invented a new and useful Rotary Well-Pump, of which the following is a specification.

This invention relates to a rotary well pump of the type wherein a plurality of 10 propeller or turbine devices are provided on a vertical shaft for lifting the liquid by successive operation of said devices. The main object of the present invention is to provide for effective lubrication of the bearings by 15 which the said vertical shaft is mounted within the pump casing. It is usual to provide a plurality of bearings for said shaft, distributed along the same, and such bearings are generally subject to considerable 20 wear on account of lack of lubrication and by reason of the scouring action of grit carried by water being pumped. My invention obviates this difficulty by providing means for forcing lubricant to the several 25 bearings along the length of the shaft.

Another object of the invention is to provide for more effective pumping action in pumps of this type. In pumps of this type it is usual to either provide a series of 30 propeller or turbine devices distributed more or less uniformly along the shaft throughout its length, or else to arrange all of said propeller devices near the lower end of the shaft. I have found that especial advantages can be obtained by combining the 35 principles of action and features of construction of both of these classes of pumps, namely, by providing a plurality of propeller devices near the bottom of the shaft 40 and by further providing a series of propeller devices distributed along the shaft between said first named propeller devices and the top of the well.

By this means I am enabled to utilize each 45 bearing member of the shaft, in the main portion of the pump casing, as a stator member, and to conveniently mount said bearing members at the joints of the casing sections, there being one stator and one propeller for each section. In order to provide 50 the requisite bearings for the shaft, it is sufficient to provide one bearing for each casing section when the casing sections are of usual length, say seven feet, but at 55 economical speeds of working it is not prac-

ticable to lift the water by one propeller through a stage of seven feet. I provide a preliminary set of propellers and stators at the lower part of the pump for giving an upward pressure or lift to the water supplementing the action of the propellers distributed along the shaft in such manner as to provide the full lift required.

The accompanying drawings illustrate an embodiment of the invention, and referring 65 thereto,

Figure 1 is a vertical section of the pump with the head portion thereof in elevation.

Fig. 2 is a detail vertical section of one 70 of the shaft bearings.

Fig. 3 is a section on line 3-3; Fig. 2.,

Fig. 4 is a detail vertical section of one 75 of the shaft bearings of the group of devices at the lower part of the shaft.

Fig. 5 is a section on line 5-5 in Fig. 4.

In Fig. 1, 1 designates the usual well casing within which is mounted in the usual manner the pump casing extending vertically and comprising a plurality of pipe sections 2 united by couplings or collars 3 80 screwed thereon in the usual manner. The pump head 4 is mounted on the upper end of the pump casing and is provided with the discharge or outlet means 5 for the water or other fluid to be pumped.

A vertical shaft 6 is mounted in suitable 85 bearings 7 and 8 on the pump head and is provided with an operating pulley 9, said shaft extending vertically and axially within the vertical pump casing and being 90 mounted in bearings 13 distributed at intervals in the pump casing. Said shaft bearings are preferably formed in spider members 10 which are attached or secured to the pump casing, for example, by annular 95 flanges 11 on said members clamped between the ends of adjacent sections 2 of the pump casing, and said member 10 being provided with arms 12 and with a central hub 13' provided with the bearing 13 through which 100 the shaft 6 passes. The member 10 constitutes not only a spider member for supporting the bearing for the shaft, but also preferably a stator member for the pumping devices, the arms 12 of said member 10 being 105 curved so as to catch the water proceeding from the next lower propeller device and direct it into a vertical course ready for the action of the next higher propeller.

At the bottom of the series of pipe 112

tions 2, the pump casing is further provided with a series of short cylinder or pump casing sections 15 each of which screws on to the pipe section next above it and contains a pumping element. Each of said pumping elements comprises a stator member formed by obliquely curved blades 16 extending inwardly from the cylindrical wall of the section 15, and a rotor member 17 carried by the pump shaft 6, the blades of the stator member 16 being curved reversely to the blades 17' of the rotor member or propeller means 17 so that each stator member will rectify or direct vertically the whirling column of water forced upwardly from the next lower propeller device.

In addition to the propeller devices 17 carried by the shaft 6, within the several pump sections 15, said shaft also carries a series of propellers or turbine rotors 19 distributed along its length preferably in such manner that one of these propellers is provided between each of the bearings of the shaft. With this construction and utilizing each of the spider supports for the bearings as a stator member, I am enabled to reduce to the minimum the cost of the installation.

In order to lubricate the several bearings for the pump shaft I provide means for forcing a lubricant, such as a suitable grease, downwardly through the shaft to the several bearings. For this purpose the shaft 6 is provided with a bore 20 communicating at its upper end with means for supplying grease and communicating through perforations 21 in the shaft with the respective bearings 13. Each bearing 13 may consist of a bearing sleeve which may be formed of Babbitt metal cast into the hub 13' as aforesaid and formed with a circumferential channel 23 communicating with perforations 21 in shaft 6. The perforations 21 in the shaft are small compared with the bore 20 of the shaft so that the lubricating grease stored in the shaft will run slowly through these perforations into the channel 23. A stuffing-box 25 is provided at the top and bottom of each hub or bearing member 13, said stuffing-box having a spring 27 for pressing the gland 28 of said box against the packing 29 so as to insure a sufficiently tight packing. A lubricated bearing such as described is preferably provided for each of the bearings 13 of the shaft along the length thereof including the top and bottom bearings for the pump. The pump may also be provided with one or more intermediate bearings such as indicated at 30 in Figs. 1, 4 and 5, said bearing comprising a Babbitt-metal sleeve within a hub 32 carried by the spider arms 16 of the corresponding stator member, said bearing sleeve being lubricated through a perforation 34 in the wall of the shaft and a perforation 35 in the wall of the bearing

sleeve 36 which is secured to the shaft and surrounds the same and which carries one of the propeller members 17. The sleeve 36 may be formed with a circumferential channel 37 communicating with the perforations 34 and 35. Similar sleeves 36 are provided for each of the propeller members and, except in the case of the pump elements provided with bearings, sleeves pass loosely through the spiders 13' of the stator members. All said sleeves are strung on shaft 6 and clamped between a collar 38 fast on the shaft and nuts 39 on the shaft. Sleeves 36 are connected by dowel pins 31 to one another and to collar 38.

The means for supplying lubricant or grease to the bore 20 in the shaft 6 may comprise the pump 40 of any suitable type whose outlet is connected by a pipe 41 to said bore and whose inlet is connected by a connection 42 to a reservoir or grease-cup 43. Check valves 45 and 46 are provided respectively in the connection 42 and at the top of the hollow shaft 6; so that, on operation of the pump 40 the grease will be drawn from the reservoir and forced through the pipe 41 to the interior or bore of the hollow shaft 6. The grease reservoir or cup 43 is preferably provided with means, such as a piston 48, pressed by a spring 49 so as to force the grease to the inlet of the pump 40. A screw 50 is shown as connected to said piston and is provided with a nut 51 whereby the piston may be drawn up against the action of the spring when it is desired to open the grease cup or reservoir for filling. In order to disconnect the grease supply means from the shaft in order to permit a rotative operation of the shaft, the pipe 41 is connected to the hollow shaft 6 by a union 50.

By operating the pump 40, the grease is forced downwardly in the bore 20 of shaft 6 and exudes through the perforations 21 and 34 in the shaft into the respective bearings 13 and 30. On account of the presence of this grease in each bearing the entrance of water carrying grit into the bearing is prevented and the effective lubrication of the bearing is insured at all times. The lubrication of the bearing is continuous, there being always a supply of grease in the hollow shaft, but said supply may be replenished whenever required by stopping the operation of the pump and coupling on the pipe 41 to the hollow shaft by means of the union 50. When the pipe has been charged with grease in the manner described, the union 50 is disconnected and the pump may then be set in operation without interference from the lubricant supply means, the check valve 46 serving to prevent escape of the grease from the shaft.

What I claim is:

1. In a rotary well pump, a vertical pump casing, a plurality of bearings mounted

therein, a shaft extending through and mounted in said bearings and provided with means for rotation of said shaft, said shaft being hollow and provided with openings 5 for communication with the respective bearings, said openings being smaller in cross section than the hollow space within said shaft, and pump means for forcing lubricant into said hollow shaft, said hollow shaft 10 having a check valve to retain lubricant therein.

2. In a rotary well pump, a vertical pump casing, a plurality of bearings mounted therein, a shaft extending through and 15 mounted in said bearings and provided with means for rotation of said shaft, said shaft being hollow and provided with openings for communication with the respective bearings, said openings being smaller in cross 20 section than the hollow space within said shaft, pump means for supplying lubricant to said hollow shaft, said shaft having a check valve at its upper end to retain lubricant therein, and stuffing-box means at each 25 end of each of said bearings, said stuffing box means being provided with packing and with springs for holding said packing in tight condition.

3. In a rotary well pump, a vertical pump 30 casing, a plurality of bearings mounted therein, a shaft extending through and mounted in said bearings and provided with means for rotation of the shaft, said shaft being hollow and provided with openings 35 for communication with the respective bearings, pump means detachably connected with the upper end of said hollow shaft for forcing lubricant into said shaft, and a check valve at the upper end of said hollow shaft 10 to retain lubricant therein when said pump means is disconnected from the shaft.

4. In a rotary well pump, a vertical pump

casing, a plurality of bearings mounted therein, a shaft extending through and mounted in said bearings and provided with 45 means for rotation of said shaft, said shaft being hollow and provided with openings for communication with the respective bearings, and means for supplying lubricant to said hollow shaft, said lubricant supply 50 means comprising a reservoir, a pump connected to said reservoir, a detachable connection between said pump and rotary shaft and a check valve between said shaft and said detachable connection. 55

5. A rotary well pump comprising a vertical pump casing consisting of a plurality of vertical sections and collars uniting adjacent sections, spider members clamped between adjacent pipe sections and formed 60 with stator blades, a series of propellers on the vertical shaft alternating with said bearings, a series of short pipe sections at the lower end of the pump casing and each provided with a stator member, and a series of 65 propeller devices on the shaft alternating with said stator members.

6. A rotary well pump comprising a vertical pump casing provided with bearings distributed along its length and with arms supporting the respective bearings and formed as curved blades operating as stator means, a shaft mounted to turn in said bearings and provided with propellers alternating with said stator means, a plurality of stator members mounted in relatively close arrangement at the lower part of said pump casing, and propeller members on the lower part of said shaft alternating with the last named stator members. 70 75 80

In testimony whereof I have hereunto set my hand, at Los Angeles, California, this 28th day of January, 1916.

FRANK J. KIMBALL.
